ATTORNEY

UNITED STATES PATENT OFFICE.

SAMUEL F. SWANTEES, OF ST. LOUIS, MISSOURI.

ADJUSTABLE CROTCH FOR UNDERGARMENTS.

Application filed July 20, 1921. Serial No. 436,117.

To all whom it may concern:

Be it known that I, SAMUEL F. SWANTEES, a citizen of the United States, residing in the city of St. Louis and State of Missouri, have invented new and useful Improvements in Adjustable Crotches for Undergarments, of which the following is a specification, reference being had to the accompanying drawings.

10 This invention is in the way of an adjustable crotch for undergarments.

After undergarments are laundered they have a tendency to shrink. The object of this invention, therefore, is to provide an 15 adjustable crotch for the undergarment which can be let out if the garment shrinks, or taken in if the garment stretches, so as to suit the comfort of the wearer.

The objects are obtained by employing co- 20 operating buttonholed and buttoned straps which are crossed and then buttoned to the undergarment, thus forming a crotch which is readily adjustable and which can be kept closed, no matter what the stretching or 25 shrinking.

In the drawings:

Fig. 1 is a frontal section of an undergarment constructed in accordance with this invention, one strap being shown in dotted 30 lines.

Fig. 2 is a frontal section showing a portion of the undergarment equipped with the button and buttonholes for fastening straps.

Fig. 3 is a detail showing the construction 35 of the straps.

This invention consists in providing a frontal crotch for the undergarment made up of two straps 1 and 2, extending up angularly from either side of the lower frontal 40 opening of the garment and forming continuations of said sides, the strap on one side, as 1, being equipped with a frontal button 3 which is adapted to button into any of the frontal buttonholes 4 cut into the 45 garment 5 upon the opposite side along a line inclined upwardly and from the perpendicular, while the strap 2 of the other side is equipped with buttonholes 6 to engage the button 7 set upwardly upon the 50 garment and to one side of the lower, frontal opening; there being a similar number of buttonholes 6 in the strap 2 as there are buttonholes 4 in the garment. Anyone of

the buttonholes 6 fasten over the button 7 sewed on the garment, and the button 3 55 fastens into the corresponding one of the button holes 4. The garment may be reinforced on the underside of the buttonholes 4 so that they will not tear out when garment pulls and stretches. Likewise as to 60 the underside of buttonholes in the strap 2. In use, by letting out or drawing up the two straps equally at each side, the frontal crotch may be lengthened or shortened, to suit the comfort of the wearer. 65

While I have herein described a certain specific method of construction of the invention, it is understood I may vary from the same in minor details, not departing from the spirit of my invention as defined in the 70 appended claims.

I claim:

1. An adjustable frontal crotch for an undergarment having a frontal button set upwardly upon the garment and to one side 75 of the lower, frontal opening thereof, and a row of frontal button holes upon the opposite side of said lower frontal opening, said button holes being cut along a line inclined upwardly and from the perpendicular; said 80 crotch comprising a strap extended up angularly from each side of said lower frontal opening and forming continuations of said sides, one of said straps having a button and the other a number of button holes, to engage the said button holes and button, respectively, of the undergarment. 85

2. In an undergarment having a frontal button set upwardly upon the garment and to one side of the lower, frontal opening 90 thereof, and a row of frontal button holes upon the opposite side of said lower frontal opening, said button holes being cut along a line inclined upwardly and from the perpendicular; an adjustable frontal crotch for 95 the garment, same comprising a strap extended up angularly from each side of said lower frontal opening and forming continuations of said sides, one of said straps having a button and the other a number of button 100 holes, to engage the said button holes and button, respectively, of the undergarment.

SAMUEL F. SWANTEES.
